US00D857050S

(12) **United States Design Patent** (10) **Patent No.:** **US D857,050 S**
(45) **Date of Patent:** **** Aug. 20, 2019**

(54) **DISPLAY SCREEN OR PORTION THEREOF
WITH GRAPHICAL USER INTERFACE**

(71) Applicant: **SAMSUNG ELECTRONICS CO., LTD.**, Suwon-si, Gyeonggi-do (KR)

(72) Inventors: **Byung-Jin Kang**, Seoul (KR); **Ji-Hyun Choi**, Seoul (KR); **Kyu-Hong Kim**, Yongin-si (KR); **Gwan-Young Yoo**, Ahnsan-si (KR); **Do-Hyung Lee**, Yongin-si (KR); **Yu-Sun Cheong**, Seoungnam-si (KR); **Byeong-Seok Choi**, Yongin-Si (KR)

(73) Assignee: **SAMSUNG ELECTRONICS CO., LTD.**, Gyeonggi-Do (KR)

(**) Term: **15 Years**

(21) Appl. No.: **29/684,492**

(22) Filed: **Mar. 21, 2019**

Related U.S. Application Data

(63) Continuation of application No. 29/626,171, filed on Nov. 15, 2017, which is a continuation of application No. 29/559,851, filed on Mar. 31, 2016.

(57) **CLAIM**

The ornamental design for a display screen or portion thereof with graphical user interface, as shown and described.

DESCRIPTION

The FIGURE is a front view of a display screen or portion thereof with graphical user interface, showing our new design.

The broken lines illustrate the display screen or portion thereof and the remainder of the graphical user interface, and form no part of the claimed design.

It is certified that error appears in the above-identified patent and that said Letters Patent is hereby corrected as shown below:

On the Title Page

Showing the illustrative figure, should be deleted and substitute with the attached title page.

In the Drawings

Delete drawing sheet 1, and substitute therefor with the drawing sheet, consisting of the FIGURE as shown on the attached page.

Signed and Sealed this
Eighth Day of August, 2023

Katherine Kelly Vidal
